UNITED STATES PATENT OFFICE.

SIMON SNYDER, OF MUNCY, PENNSYLVANIA, ASSIGNOR TO SPROUT, WALDRON AND COMPANY, OF BOROUGH OF MUNCY, PENNSYLVANIA, A CORPORATION OF PENNSYLVANIA.

QUICK-RELEASE DEVICE FOR GRINDING-MILLS.

SPECIFICATION forming part of Letters Patent No. 740,479, dated October 6, 1903.

Application filed June 26, 1902. Serial No. 113,339. (No model.)

To all whom it may concern:

Be it known that I, SIMON SNYDER, a citizen of the United States, residing at Muncy, in the county of Lycoming and State of Pennsylvania, have invented certain new and useful Improvements in Quick-Release Devices for Grinding-Mills; and I do hereby declare the following to be a full, clear, and exact description of the invention, such as will enable others skilled in the art to which it appertains to make and use the same.

This invention relates to attrition-mills, and particularly to quick-release devices for effecting instant separation of the burs or disks to permit the passage of any foreign substance liable to injure the grinding-surfaces or to allow the mill to run without grinding.

The principal objects of the invention are, first, to provide a simple and efficient device of this character whereby the grinding-surfaces may be instantly released and separated, and, second, to combine said quick-release with improved adjusting devices for yieldingly holding the grinding-surfaces together and regulating the pressure between them in accordance with the quality of work desired, the arrangement being such that the runner-heads or disks or burs may be separated without affecting said adjusting devices and may quickly be brought together again in their former position without the necessity of any readjustment.

The invention will hereinafter be first fully described with reference to the accompanying drawings, which form a part of this specification, and then pointed out in the claims following the description.

In said drawings, Figure 1 represents in perspective a portion of an attrition-mill with my improved quick-release device applied thereto. Fig. 2 is a horizontal section of the quick-release device and connections in position for maintaining the grinding-surfaces together. Fig. 3 is a longitudinal vertical section of the same. Fig. 4 is a longitudinal vertical section of a spring-actuated device co-operating with the quick-release to separate the grinding-surfaces when released; and Fig. 5 is a vertical cross-section through

the quick-release device, showing the same 50 in releasing position.

Referring to the drawings by specific letters of reference, A designates the base of an attrition-mill, and B B denote standards rising therefrom and supporting in suitable 55 bearings a driving-shaft C, to which power may be applied at pulley D. The driving-shaft carries a runner-head or grinding plate or disk within the casing E, the grinding-surface of which confronts a similar grinding-surface, which may be either rotary or stationary.

The letter F denotes a casing which is bolted to the rear shaft-bearing or otherwise fixed in place. Slidably arranged therein is a step-box G, in which the end of the driving-shaft is journaled. The rear end of this step-box projects beyond said casing and is exteriorly threaded and has screwed thereon another casing H, which may be considered as a rearward extension or adjustable part of the step-box. At its forward end the step-box is formed with a flange or shoulder g, slidably fitting within the casing F, and a stout spring I is interposed between said shoulder g and 75 an internal flange or shoulder f, formed at the rear of the casing. The force of this spring thus presses the step-box and casing H forwardly, the movement being limited by abutment of the front end of the casing H 80 against the rear end of the casing F. In order to prevent the casing H from turning, a pin J may be inserted through registering apertures in lugs or ears on the two casings and held in place by a set-screw j. On loosening the set-screw and withdrawing the pin the casing H, with parts supported thereby, may be given one or more complete turns either to the right or left, thus screwing or unscrewing on the step-box and adjusting the 85 tension of the spring I.

The end thrust of the driving-shaft is received within the step-box by a short shaft section or block K, a suitable antifriction device being preferably interposed between the 95 end of the shaft and the block. Said antifriction device, as shown, consists of two chilled plates L L and an interposed series of

balls. The block K projects back into the casing H and there abuts against a cam device M, consisting of a short transversely-disposed cylinder or spindle having a greater 5 and a lesser diameter or cut away, preferably, at opposite sides to form flat faces, as shown in Fig. 3. This cam device in the construction illustrated is formed with an axial polygonal bore or opening, in which is fitted a 10 similarly-formed stem or rod N, the projecting ends of which are rounded and mounted as journals in longitudinal slots h in the casing H. At one end the stem is formed or provided outside the casing with a lever or 15 handle O for turning the cam device. Movement of the latter may be limited to a quarter-turn in either direction by a lug m thereon, adapted to engage suitable notches or stops h' within the casing, Fig. 5, or by other 20 suitable means. The stem has at its handle end a flange or head n, the flat inner face of which rides over the outer side of the slot h in the casing, and a flat washer or cup n' is screwed or fastened to the opposite end of the 25 said stem and rides over the outer side of the corresponding slot. Said flange and washer insure steady movement of the cam device in turning, and the construction holds the parts well in place, but permits ready detachment. 30 It will be understood, of course, that any equivalent form of cam device may be used and that the same may be mounted within the casing in any suitable manner.

The letter P denotes a bearing-plate transversely disposed and slidably arranged within the rear end of casing H. A temper-screw Q, provided with a suitable hand-wheel, is screwed through the rear end of said casing, and its inner end abuts said bearing-plate, 40 holding it against the cam device and opposing the end thrust of the driving-shaft. The stem of the temper-screw is also screwed through a lock-nut R, preferably of the winged or finger type for manipulation of the 45 same.

When the lever O is horizontal, as shown in Fig. 1, the cam device is in the position shown in Figs. 2 and 3, with its greater diameter interposed between plate P and block 50 K. In this position of the cam device, the temper-screw Q being properly adjusted, the driving-shaft is held in its extreme forward position, thus maintaining the grinding-surfaces together or in proper grinding relation. 55 The temper-screw may be adjusted from time to time to compensate for wear of the anti-friction devices or to regulate the pressure between the grinding-surfaces, as may be found necessary. The force of the spring I 60 is constantly exerted in pressing forward the step-box, with the driving-shaft, block, cam device, and temper-screw, thus holding the grinding-surfaces yieldingly together, and, as before mentioned, the tension of said spring J 65 may be adjusted by withdrawing the pin J and screwing or unscrewing the casing H on the step-box.

When it is desired to release the grinding-surfaces, the lever O is quickly thrown up to vertical position, as shown in Fig. 5, thus interposing the shorter diameter of the cam device between the bearing-plate and block, which allows the driving-shaft to move back a distance equal to the difference between the greater and smaller diameters of the cam device and the grinding-surfaces to separate the same distance. To resume grinding, the lever is again thrown down to horizontal position, and the pressure devices having been previously adjusted it is obvious that on 80 throwing down the lever the grinding-surfaces will be brought in exactly the same position for grinding as before. The slots h permit the cam device to slide back and forth when turned from one position to another, also permit longitudinal play thereof when the temper-screw is adjusted, and take all strains off the journals of said cam device. 85

In connection with the quick-release I preferably employ a spring-actuated device adapted to separate the grinding-surfaces the instant the lever O is operated to release the pressure between them. The device herein illustrated, Figs. 1 and 4, consists of a coiled spring S, interposed between a loose sleeve or 90 washer T and a fixed collar U, which are placed on the driving-shaft between its front or inner bearing and the hub of the pulley D. The collar U is secured on the shaft by a set-screw and recessed to house the spring, which 95 has one end seated in a socket in said collar and the other end seated in a socket in the washer or sleeve T. When the quick-release is operated, the spring, acting against the fixed collar, immediately pushes back the shaft, as 100 shown in Fig. 5, where a separation appears between the collar and loose sleeve or washer. In this position the mill can run safely any 105 length of time without injury to the grinding-surfaces, since the spring prevents them from 110 coming together. While in motion very little force is required to separate the runner-heads or disks, and hence the spring S is made 115 weaker than the pressure-spring I, so as to prevent counteracting the effect of the latter when the disks are grinding.

I thus provide an exceedingly simple and efficient quick-release device whereby the mill-operator is enabled with little effort to throw the grinding disks, burs, or plates out of action or bring them together in an instant or within the brief interval of time required to move the operating-lever through its short turn. The release action requires a minimum of effort and is practically instantaneous, for 120 by reason of the interposition of the curved faces of the cam device between the bearing-plate and block a very slight pressure or lift on the lever will turn the cam device sufficiently to bring its opposite corners in line 125 between the plate and block, whereupon force of the springs I and S will complete the turn, as is obvious. A little greater force is required for bringing the disks together, since 130

the flat faces of the cam device must be turned against force of the springs, and this is amply sufficient to prevent the grinding-surfaces from running together prematurely or by accident. My improved device also permits all the ordinary adjustments required for grinding to be made freely and easily and possesses all the strength and rigidity of a solid support for the driving-shaft.

It will be observed that the lever O in its horizontal position acts as a weight, and thus prevents the quick-release device from being operated by accident, yet when it is desired to release the grinding-surfaces a slight lift or stroke on the lever is sufficient, owing to the advantageous arrangement of the cam device and co-operating parts. On the other hand, when the lever is in vertical position sufficient effort is required to throw it down to prevent such movement by accident, as before explained. This is an advantageous feature, and the arrangement described is therefore preferred, though the invention is not restricted thereto, since any suitable means may be used for operating the cam device and stopping the same in its proper position.

While my improved quick-release is preferably combined with a spring-actuated step-box, as herein shown and described, it will be understood that the releasing device is not restricted to such or any special form of bearing, but may be otherwise applied. The device is also susceptible of various changes in details of construction and arrangement without departing from the scope of my invention.

Having thus fully described my invention, what I claim, and desire to secure by Letters Patent of the United States, is—

1. In a quick-release mechanism, the combination with the runner-shaft, of an end-thrust-sustaining member therefor, and a cam device between said member and the end of said shaft adapted in one position to hold the shaft forward and in the other position to permit it to move backward, and means for turning said cam device; substantially as described.

2. In a quick-release mechanism, the combination with the runner-shaft, of a member adapted to sustain the end thrust thereof, an interposed cam device having a greater and a lesser diameter, and means for turning said device to bring either its shorter or longer diameter between the shaft and said member; substantially as described.

3. In a quick-release mechanism, the combination with the runner-shaft, of a member sustaining end thrust thereof, an interposed cam device having a greater and lesser diameter, and means for turning said cam device to place either its shorter or longer diameter between said shaft and member, with provision whereby said cam device can shift back and forth longitudinally when turned; substantially as described.

4. In a quick-release mechanism, the combination with the runner-shaft, of a bearing-plate, a cam device arranged between said plate and the end of the shaft consisting of a cylinder or spindle cut away at opposite sides to leave two opposite curved faces and two opposite flat faces, and means for turning said cam device; substantially as described.

5. In a quick-release mechanism, the combination with the runner-shaft and its step-box or casing, of a member in said step-box adapted to sustain the end thrust of said shaft, an interposed cam device for controlling the shaft having its bearings in longitudinal slots in the step-box, and means for turning said cam device; substantially as described.

6. In a quick-release mechanism, the combination, with the runner-shaft and its step-box, of a temper-screw for adjusting said shaft entered through the rear of said step-box, a cam device for positioning and releasing the shaft interposed between said screw and the end of the shaft, and means for turning said cam device; substantially as described.

7. In a quick-release mechanism, the combination, with the runner-shaft and its step-box, of a cam device for positioning and releasing the shaft having its bearings in longitudinal slots in the step-box, means for turning said cam device, and a temper-screw for adjusting the shaft entered through the rear of the step-box and acting against the cam device; substantially as described.

8. In a quick-release device, the combination with the runner-shaft and its step-box, of a block receiving the end thrust of the shaft, a bearing-plate slidably arranged in the rear of the step-box, a temper-screw acting against said bearing-plate, a cam device arranged between the bearing-plate and block, and means for operating said cam device to release the shaft or restore it to its normal position; substantially as described.

9. In a quick-release device, the combination with the runner-shaft and its step-box, of a block in said box receiving the end thrust of the shaft, a bearing-plate and a temper-screw acting against said plate, a cam device arranged between the plate and block having a greater and a smaller diameter and having longitudinally-movable bearings, and means for turning said cam device; substantially as described.

10. In combination with the runner-shaft, a spring-actuated yieldable step-box, a cam device carried thereby adapted to receive the end thrust and position or release the shaft, and means for operating said cam device; substantially as described.

11. In combination with the shaft, a fixed casing, a spring-actuated step-box for the shaft slidably arranged therein and having a rearward adjustable part or casing which limits its forward movement by abutment against

- said fixed casing, and an independent quick-release device for controlling the shaft mounted in and movable with said adjustable casing; substantially as described.
- 5 12. In combination with the shaft, a fixed casing, a spring-actuated step-box for the shaft slidably arranged therein, a member screwed on said step-box and limiting its forward movement by abutment against the fixed casing, and independent shaft-controlling means mounted in and movable with said member; substantially as described.
- 10 13. In combination with the shaft, a fixed casing, a step-box for the shaft slidably arranged therein, a spring interposed between suitable stops on said casing and step-box, a member or casing screwed on the rear end of the step-box and limiting its movement by abutment against said fixed casing, said member being adapted to be turned for adjusting tension of the spring, and an independent quick-release device for controlling the shaft

carried by said step-box; substantially as described.

14. In a quick-release mechanism, the combination with the runner-shaft, of a member sustaining end thrust thereof, and an interposed cam device adapted in one position to hold the grinding-surfaces together and in another to permit them to separate, a handle 25 for turning said cam device, and means for limiting its turn to said positions, with means whereby a slight pressure on the handle will cause the cam device to turn to release the grinding-surfaces while a greater effort is required to turn it to bring the surfaces together.

In testimony whereof I affix my signature in presence of two witnesses.

SIMON SNYDER.
